(57) **CLAIM**

The ornamental design for a protective eye goggle, as shown and described.

DESCRIPTION

FIG. 1 is a rear elevational view of a protective eye goggle, showing another embodiment of my new design;

FIG. 2 is a top plan view thereof;

FIG. 3 is a top perspective view thereof;

FIG. 4 is a side elevational view thereof, the opposite side elevational view being identical;

FIG. 5 is a bottom plan view thereof; and,

FIG. 6 is a front elevational view thereof.
